(57) **CLAIM**

The ornamental design for a window flashing product, as shown and described.

DESCRIPTION

FIG. 1 is a front perspective view of a first embodiment of the window flashing product with an upper flap thereof in an open position, and indicating portions thereof that are illustrated in detail in FIG. 10 and FIG. 11;

FIG. 2 is a front perspective view of the window flashing product of FIG. 1, with the upper flap in a sealed position;

FIG. 3 is a front elevation of the window flashing product of FIG. 1, with the upper flap in the sealed position;
FIG. 4 is a side elevation of the window flashing product of FIG. 1, with the upper flap in the open position, an opposing side view being a mirror image thereof;
FIG. 5 is a side elevation of the window flashing product of FIG. 1, with the upper flap in the sealed position, an opposing side view being a mirror image thereof;
FIG. 6 is a top plan view of the window flashing product of FIG. 1, with the upper flap in the sealed position;
FIG. 7 is a bottom plan view of the window flashing product of FIG. 1, with the upper flap in the sealed position;
FIG. 8 is a rear elevation of the window flashing product of FIG. 1;
FIG. 9 is a rear perspective view of the window flashing product of FIG. 1, with the upper flap in the open position;
FIG. 10 is a front perspective detail view of an upper corner of the window flashing product of FIG. 1, with the upper flap in the open position;
FIG. 11 is a front perspective detail view of a lower corner of the window flashing product of FIG. 1;
FIG. 12 is a front perspective, exploded view that shows environmental structure in the form of an exterior surface of a building with an aperture therein, the window flashing product of FIG. 1 with the upper flap in the open position to be

installed within the aperture, and environmental structure in the form of a window to be installed within the window flashing product;

FIG. 13 is a front perspective view that shows environmental structure in the form of an exterior surface of a building, the window flashing product of FIG. 1 with the upper flap in the sealed position installed therein; and, environmental structure in the form of a window installed within the window flashing product;

FIG. 14 is a front perspective view of a second embodiment of the window flashing product;

FIG. 15 is a front elevation of the window flashing product of FIG. 14; and,

FIG. 16 is a side elevation of the window flashing product of FIG. 14, a top view being identical thereto, an opposing side view and a bottom view being mirror images thereof.

In all of the drawings, broken lines indicate environmental structure that forms no part of the claimed design.

A rear elevation and a front perspective detail view of the second embodiment that is shown in FIGS. 14 through 16 are identical to the rear elevation and front perspective detail view of the first embodiment that are shown in FIG. 8 and FIG. 11 respectively.
